UNITED STATES PATENT OFFICE

ALFRED WALCHER, OF CHICAGO, ILLINOIS, ASSIGNOR TO GENERAL STEEL CASTINGS CORPORATION, OF RIDLEY TOWNSHIP, PENNSYLVANIA, A CORPORATION OF DELAWARE

METHOD OF FORMING COMPOSITE MOLDS FOR CASTING METALS

Application filed August 11, 1932. Serial No. 628,329.

This invention relates to improvements in the art of molding and particularly to a novel method of forming molds of the type composed of the plurality of independent sections adapted to be fitted together to form the completed mold.

Molds used for casting large castings are very difficult to form as an integral, unitary construction and in such instances, individual mold sections may be made from corresponding parts of the casting pattern, whereby upon assembling the sections thereof, a completed mold results.

An example of this type of mold is described and claimed in the patent to Weaver, No. 1,233,151, illustrating a mold adapted for large castings made up of three sections. Molds of this type are particularly useful for casting large frames, such as for instance, truck frames for railway cars, locomotives and like castings. Whereas molds of the type illustrated by Weaver have been used with a high degree of success, it has been found in practice that certain difficulties are met with due to the joints that result between the composing sections.

It is obvious that a crack is left between adjacent sections into which a portion of the molten metal may flow forming a flange which must be removed and resulting in an undesirable finish and a more or less imperfect part in the casting. Furthermore, those portions of the sand adjacent the joint are more subject to damage and frequently break or wash away during the pouring operation, resulting in an imperfect casting.

It is the object of this invention to utilize the advantages afforded by a sectional mold, yet provide a new and improved joint and process of producing same whereby the above mentioned difficulties are avoided.

The process of this invention utilizes the principle of forming each composite section of the mold from corresponding sections of the pattern but forming each section of slightly less length than would be required for forming the complete mold upon bringing the sections into abutting relationship. Each section is formed in a section of the flask of proper length for end to end attach-

ment to the adjacent section but during the operation of tamping the sand around the pattern the end of the mold section adapted for abutting attachment with the next adjacent mold, is provided with a temporary wall which extends into the mold, providing insufficient space for a complete mold section.

In practice, it results that the flask sections may be attached end to end, but when so arranged, the metal receiving cavities formed in accordance with the pattern sections are of insufficient length to come into abutting relationship. Accordingly, when the mold sections are assembled, there is left in the sand portions thereof, a space which may conveniently be from 4 to 12 inches in ordinary practice at the location of the joints between adjacent sections.

At this point in the mold forming operation, dummy patterns are used which are formed as short sections of shape corresponding to that portion of the casting to be formed at the location of the joints. These dummy patterns are of length sufficient to safely bridge the space referred to and after being placed in position, enable the completion of the mold by a further sand tamping operation. Sufficient sand is tamped into the space referred to to complete the mold which thereby provides a metal receiving cavity of continuous formation free from joints, cracks or other imperfections which would otherwise be present. Thereafter, the dummy patterns may be withdrawn, and a suitable closing or top section placed over the mold so formed. The mold, so completed, is then ready for the pouring operation.

In order to illustrate this invention one preferred form is hereinafter described in connection with the accompanying drawings in which:

Figure 1 is a perspective view of the lower half of a mold section with the temporary wall in place prepared for tamping the sand around the corresponding pattern section; and

Figure 2 is a perspective view of a completed lower half of a mold, in this in-

stance composed of two sections showing the molded sand forming the metal receiving cavity and with the dummy patterns in place. This figure also illustrates the condition of the mold while applying sand in the space allowed at the location of the joint; and

5 Figure 3 is a plan view, partly in cross section of the mold formed as illustrated in Figure 2;

10 Figure 4 is a side elevational view of Figure 3 and

15 Figure 5 is an elevational view in cross section taken on the line 5—5 of Figure 3 and looking in the direction of the arrows;

20 Figure 6 is an elevational view of the mold section illustrated in Figure 1, showing the end to which the temporary wall is applied;

25 Figure 7 is a fragmentary elevational view taken on the line 7—7 of Figure 6, and looking in the direction of the arrows;

30 Figure 8 is a side elevational view in cross section at the location of the joint between adjacent sections of the mold. This figure is taken on line 8—8 of Figure 9, looking in the direction of the arrows.

35 Figure 9 is a cross sectional view taken on line 9—9 of Figure 8, and looking in the direction of the arrows and

40 Figure 10 is a side elevational view of a modified form of this invention, illustrating a mold composed of three sections.

45 By referring to the drawings it will be noted that each section is made of frame-like construction having side walls preferably of metal and properly reinforced which may if desirable, be formed of independent wall sections bolted, riveted or otherwise secured together. As shown in Figure 1, each section of the mold here illustrated is composed of wall 10, which constitutes a section of the side wall of the completed mold, wall 11 forming an end wall of the mold, and a wall 12 which extends only part way of the vertical height of the mold section.

50 The remaining portion of the wall is supplied by a temporary wall 13, removably held in position with its inner wall surface flush with the inner surface of wall 12. It is to be understood that each section is formed in this manner; and in cases where more than two sections are employed in 55 composing the finished mold the intermediate sections will have two opposite walls provided with temporary wall portions.

60 It should be noted that the inner surface of walls 12 and 13 are inwardly to some extent from the outer abutting edges of the mold sections so that the pressed sand portion of the mold will be of less length than the jointure between the walls of adjacent sections.

65 In forming the mold in practice, a base

70 plate 14 is provided, to which is attached a section of the pattern 15. The base plate is preferably securely fastened after which the mold section with the temporary wall 13 in place, is positioned thereover as shown in Figure 1, with the temporary wall downwardly and in abutment with the end surface 16 of the pattern section. The mold section in this position is inverted as compared to the pouring position. That is to say, after tamping, it will be turned over in accordance with usual mold-forming practice. The mold is positioned and fixed with respect to the pattern by means of pins 15', which fit into properly located openings in the base plate 14. With the mold section so positioned the usual tamping operation is carried out whereby a properly formed sand cavity results.

75 After the pattern is covered, it is preferable to provide a reinforcement of suitable construction, such as, for instance, the grate work 16', which in this illustration, is provided with extending ends received in openings 17 and held by wedges. After 80 location of the reinforcement, the sand tamping operation is continued until the mold section is filled.

85 By a similar process, all sections of the mold are completed, and thereafter each is lifted from the base plate 14, free of the sand forming pattern. Each section is then turned upside down and positioned for assembly. In the form of mold here illustrated, composed of two sections, the sections are fitted together as shown in Figure 2, and held by locking pins 18.

90 Prior to assembly the temporary wall 13 of each section is removed, leaving the adjacent portion of the tamped sand and the end of the metal receiving cavity exposed.

95 In assembled relationship adjacent wall sections 12 fit in cooperating relationship as shown in Figure 8. It is then preferable to place a metallic strip 20 over the crack located between the edges of the wall section 12 so as to assist in forming a crack free joint in the sand. Strip 20 is clearly shown in Figures 8 and 9. With the mold section so assembled, dummy patterns 21 are placed in position at the location of the joint so as to safely bridge the space 22 left at the joint. The mold is then completed by continuing the tamping operation to fill the cavities 22 with sand, which is tightly packed to form a complete unitary mold. Thereafter the dummy patterns are withdrawn.

100 The mold so formed is then ready for receiving the top closing portion which may be of any suitable form. For instance, it may comprise a plurality of sections somewhat similar to the lower half of the mold but perhaps of less height and with or without sand reinforcing means similar to the 105

grate improvement 16. If desired, the mold may be closed by suitable baked sand blocks or plates provided with adequate pouring openings and clamped in place by 5 metal braces attached to the lower half of the mold.

It is found in practice that molds constructed in accordance with this invention may be made of any suitable size and 10 formed of any number of sections. The novel and improved method herein described of forming the joints results in perfect and continuous molding services at the location of the joints between sections 15 whereby all of the difficulties heretofore encountered attending the use of sectional molds, are eliminated.

It is to be understood that individual mold sections may be made of any suitable 20 or convenient form and may, if desired, comprise a plurality of individual walls bolted, riveted or otherwise secured together. In the present illustration, the pattern shown represents a four wheel truck 25 frame for railway cars, and here, like in many other instances, the two mold sections are duplicates.

In cases where symmetrical castings are formed, certain mold sections may be duplicates and therefore fewer pattern sections 30 are required. As in such cases, the end sections and intermediate sections are frequently duplicates respectively, one of the other.

35 The invention is not to be limited by the particular illustration herein given as it is obvious that this invention covers broadly the process of producing a mold involving the novel steps herein described for providing a smooth and continuous joint.

I claim:

1. The improvement in the art of casting which includes providing a mold in sections, each section of which is formed from a corresponding portion of the pattern, but being of such length as to provide space between adjacent sections when assembled in relationship to form the finished mold, assembling the sections in proper relationship to 50 complete the mold, placing dummy patterns in proper relationship across the space so provided and completing said mold by tamping operations in the manner to eliminate cracks at the joints.

55 2. The improvement in the art of casting which comprises forming a sectional mold by providing individual mold sections adapted for joining, one to the other to form the completed mold, each provided with a temporary wall, at the side or sides to be joined, employing corresponding pattern sections for each mold section, and tamping sand impressions from said pattern sections with the joining ends thereof in abutment with said 60 temporary walls, forming said mold sections 65

in the above described manner of insufficient length to complete the mold when in assembled relation, assembling said mold sections for completing the mold and completing said mold by a second tamping operation with 70 the employment of dummy patterns.

3. In the art of making composite molds for large castings from individual sections, the steps of forming individual sections from corresponding sections of the pattern, each of insufficient length to complete the mold when assembled, assembling said sections in the proper relationship whereby a space is provided at the joint, placing dummy patterns across said joints and completing said 80 mold by a second tamping operation.

Signed at Chicago, Illinois, this 30th day of June, 1932.

ALFRED WALCHER.
